UNITED STATES PATENT OFFICE

162,968

MACHINE FOR MAKING AND STORING ICE CUBES

Thomas T. Lunde, Mill Valley, Calif., assignor to
Lacon Corporation, a corporation of California

Application January 12, 1951, Serial No. 13,773

Term of patent 7 years

(Cl. D67—3)

To all whom it may concern:

Be it known that I, Thomas T. Lunde, a citizen of the United States of America, residing at 100 Eldridge Avenue, Mill Valley, California, have invented a new, original, and ornamental Design for a Machine for Making and Storing Ice Cubes, of which the following is a specification, reference being had to the accompanying drawing:

Figure 1 is a top plan view of the machine for making and storing ice cubes, embodying the invention of the design;

Figure 2 is a view in side elevation of the machine; and

Figure 3 is a view in front elevation of the machine.

I claim:

The ornamental design for a machine for making and storing ice cubes, substantially as shown.
THOMAS T. LUNDE.
